UNITED STATES PATENT OFFICE.

CHARLES P. VAN GUNDY, OF CATONSVILLE, MARYLAND.

RAILWAY SIGNAL-TORPEDO.

1,167,450.

Specification of Letters Patent.

Patented Jan. 11, 1916.

Application filed January 3, 1914. Serial No. 810,109.

To all whom it may concern:

Be it known that I, CHARLES P. VAN GUNDY, a citizen of the United States, residing at Catonsville, in the county of Baltimore and State of Maryland, have invented certain new and useful Improvements in Railway Signal-Torpedoes, of which the following is a specification.

My invention relates to improvements in railway signal torpedoes, and more particularly to that class thereof adapted to be secured upon a rail and to be exploded by the wheel of a train.

The objects of my invention are: First, to provide a torpedo in which the explosive charge is securely held and wrapped in a single piece of paper, or other suitable non-flying material, and said paper is so distributed about the charge that the possibility of moisture passing into the charge is eliminated. Second, to provide a torpedo in which the wrapper is so cut and scored that a single blank is capable of being quickly folded and uniformly distributed about the charge, and the fastening strip is securely attached to the torpedo and removed from the zone of dispersion of the explosive. Third, to provide a torpedo which is of the simplest and safest form, easily and cheaply manufactured, and of long life without deterioration, and readily secured to a rail. Fourth, other advantages and objects of the invention will appear from the detailed description to be hereinabove given.

The invention consists of structural features and relative arrangements of the elements which will be hereinafter more fully described and particularly pointed out in the appended claims.

In the drawings in which similar reference characters indicate the same parts in the several figures of drawing, Figure 1 is a blank from which the torpedo is formed; Fig. 2 is a blank of a modified form; Fig. 3 is another blank of a modified form; Fig. 4 is a side view of a section of rail with completed torpedo attached; Fig. 5 is a perspective of the explosive charge within the torpedo; and Fig. 6 is a perspective view of the torpedo.

Referring to Fig. 1, the numeral 1 represents a blank of any suitable non-flying material, such as tough paper, which is provided near its upper edge with preferably

two horizontal scores 2 and 3, and two vertical scores 4 and 5, and a central score 6, and side cuts 7 and 8, thus dividing the blank into small rectangular upper sections 9, 10, 11, 12, 13 and 14, central sections 15, 16 and 17, and lower sections 18, 19 and 20. The manner of forming the torpedo from the blank shown in Fig. 1 is as follows: The torpedo charge 21, as shown for example in Fig. 5, is placed on the central section 16, sections 15, 12 and 9 are folded on line 5 until they rest upon sections 16, 13 and 10, respectively, then sections 17, 14 and 11 are folded on line 4 upon sections 15, 12 and 9, respectively. Sections 18, 19 and 20 are then folded on scored line 6, and the section 19 is folded upon and secured by any suitable adhesive to the back of section 17. The section 20 is folded on the scored line 4 and secured to the other or back side of the section 16 from that of sections 15 and 17. Section 18 is folded on line 5 down upon and secured to the back side of section 20. The fastening strip 22, of lead or other suitable material, is then placed centrally upon the back side of sections 12, 13 and 14, and the sections 9, 10 and 11 are folded on line 2, respectively, over on the fastening strip 22 and on sections 12, 13 and 14, and on the same side as sections 18 and 20 now appear. Superposed sections 9, 10, 11 and 12, 13 and 14 are then folded on the central section of line 3 over on the upper portions of sections 15, 16 and 17. After the sections are folded as above indicated, into the form as shown in Fig. 6, a staple 23, or other fastening means is passed through the sections 9, 10, 11, 12, 13, 14, 15, 16 and 17, in their folded position, and the fastening strip 22, and a finished torpedo, as shown in Fig. 6, is produced. During the above operations any suitable adhesive may be applied to any of the contacting faces of superposed sections and the whole cartridge may be dipped in any suitable water-proofing composition, such as shellac, gum, or asphaltum, if so desired.

While the preferred manner of making the torpedo is to place the folded sections 9, 10, 11, 12, 13 and 14 on the same side of the torpedo in order to be enabled to engage the upper edges of the folded sections 18 and 20, I do not limit myself to this particular arrangement.

To apply the completed torpedo to the

track, all that is necessary, is to place the torpedo flat on top of the rail, as shown in Fig. 4, with the ends of the fastening strip bent under the head of the rail and with the fastening strip nearest to the point of approach of the train, so that the wheel moving in the direction of the arrow *a*, will first grip the fastening strip before passing over the torpedo proper, and cartridge. It will also be seen that by attaching the fastening strip on the end as shown, the possibility of the explosion of the cartridge scattering the metal of the fastening strip, is eliminated.

In the form of blank shown in Fig. 2, the invention is substantially the same as that shewn in Fig. 1, with regards to the scores, cuts and sections, with the exception that instead of the cuts 8 and 7 being separated by a score 6, as shown in Fig. 1, the cut 7 and score 6 have exchanged positions, and the cuts 8' and 7' are adjacent each other, and the score 6' is on the outside, as shown in Fig. 2. In the use of the blank shown in Fig. 2, after the cartridge has been placed on section 16, sections 9, 12, and 15 are folded on score 5 upon sections 10, 13 and 16, and then sections 17, 14 and 11 are folded on score 4 upon the top of or back of the sections 15, 12 and 9, respectively. Section 20 is then folded on score 6', on the back of section 16, section 19 is folded on score 4 on the back of section 17, and section 18 is folded on score 5 upon the back of section 20. The sections 9, 10, 11, 12, 13 and 14 in their folded positions are folded on the folded position of the score 3, after the fastening strip has been properly placed, and the operations again carried out as explained in the directions with reference to the blank shown in Fig. 1.

In the blank shown in Fig. 3 the arrangement of cuts, scores and sections, is similar to that shown in Fig. 2, with the exception that the blank is reversed, and another series of sections 24, 25, 26 and 27, and scores 2', 3', 4' and 5', have been added, as indicated. In the use of the blank shown in Fig. 3, the cartridge is placed on section 17, sections 24, 25, 26 and 27 are folded on score 4' on sections 20, 17, 14 and 11, respectively. Sections 16, 13 and 10 are folded on score 4, so that sections 16, 13 and 10 rest upon the backs of sections 25, 26 and 27, respectively. Sections 15, 12 and 9 are then folded on score 5 so that they rest upon the backs of sections 17, 14 and 11, respectively. Sections 24 and 20 in their folded position, and face to face, are then folded on the registering scores 5' and 6', until the back of section 24 rests against the back of section 16, then the section 19 is folded on score 4 until the back of section 19 rests on the back of section 15, and the back of section 18 is then folded on the score 5

against the back of section 20. The sections 9, 10, 11, 12, 13, 14, 26 and 27 in their folded positions are then folded on the scores 2, 2', 3 and 3' as previously explained, after the fastening strip 22 has been properly placed. It will be understood that adhesive material may be applied between the sections during the folding operations, in order to firmly secure the same together.

From the foregoing disclosure of forming the blank and folding the same about the section of explosive, it will be seen that all the material in the blank is utilized to evenly distribute the paper about the explosive, and at the same time have a closed and tight bottom to prevent the explosive from dropping out, and firmly securing the fastening strip for the torpedo, and seal the free ends of the folded blank by one operation or securing means.

While I prefer to attach the fastening or securing strip 22 by means of the uppermost sections 9, 10, 11, 12, 13 and 14, in their folded position, as herein described, and have found the same expedient and cheap to manufacture, it will be readily understood that the fastening strip 22 could be secured to the container with the use of only one of the sections 12, 13 or 14, or without the use of any of these sections, as by simply passing the fastener or staple 20, through the fastening strip 22 and the upper portions of the sections 15, 16 and 17. Of course it will be also understood that the explosive charge of the torpedo may be in a solid or powder form, and inclosed in any suitable envelop, if so desired, before being inclosed in the single piece wrapper.

What I claim is:—

1. A railway or like torpedo comprising a single rectangular piece of pliable sheet material scored to divide said sheet into a plurality of upper and a plurality of lower rectangular sections, one of said lower sections being separated from and independent of the upper sections and attached to a lower section, and a lower section attached to an upper section, said upper sections folded upon each other and the lower sections folded upon and around the upper sections, thereby forming a container with a plurality of superimposed layers of said material and a closed bottom, a suitable explosive material within the container, and suitable means attached to one end of the container for holding the torpedo on the railway track.

2. A railway or like torpedo comprising a single rectangular piece of pliable material scored to divide said sheet into more than two upper, more than two central and more than two lower rectangular sections, two of said lower sections being cut or separated from the central sections, and the other lower sections attached to the central sections, said central sections folded upon each

other, and the lower sections folded upon and around the central sections, thereby forming a container having its sides formed of a series of superimposed layers of said 5 pliable material and a closed bottom, a suitable explosive material within the container, and a pliable strip at one end of the container and surrounded by the upper sections

of the sheet when folded for holding the torpedo on the railway track.

In testimony whereof I affix my signature 10 in presence of two witnesses.

CHARLES P. VAN GUNDY.
